All Drawings

Des. 1483

Atchol No. 1483.

Henry Terry, of Plymouth, Conn.
Letters Patent No. 118, dated Oct. 22, 1861.

The schedule referred to in these Letters Patent and making part of the same.

To all whom it may concern;

Be it known that I, Henry Terry, of Plymouth, County of Litchfield, and State of Connecticut, have invented or produced a new and original design for a Clock Case Front, and I do hereby declare that the following is a full and exact description of the same, referring to the accompanying photographic views, in which the same letters indicate like parts.

In the accompanying photographic views is shown a new and original design for a clock case front.

a, is the case proper.

b, is a plane, or moulded base.

c, is a plane, or moulded sash, or door.

d, is a plane rounded sash, or door.

e, is the dial.

The whole combined substantially in the manner shown and described, to produce a highly ornamental design for a clock case front.

What I claim therefore and desire to secure by Letters Patent, is the design for a clock case front, substantially as herein above described and illustrated.

In testimony whereof, I have hereunto set my hand and affixed my seal this 24th day of June 1861.

E.G.S.

C. W. Fowler.

1483

Henry Terry. (seal)
